USPC ..... D14/485—495
 CPC ... B60K 37/00; G06F 3/0481; G06F 3/04845;

The ornamental design for the display screen with graphical user interface, as shown and described.

G06F 3/04817; G06F 17/212; G06F 19/3406; G06T 13/80; G06T 15/02

DESCRIPTION

See application file for complete search history.

FIG. 1 is a display screen with graphical user interface of a first embodiment showing our new design;

(56) **References Cited**

FIG. 2 is a display screen with graphical user interface of a second embodiment showing our new design; and,

U.S. PATENT DOCUMENTS

FIG. 3 is a display screen with graphical user interface of a third embodiment showing our new design.

D297,644 S * 9/1988 Sugiyama D16/219

The outermost set of broken lines and the broken line showing of rounded shapes illustrate an electronic device,

5,835,094 A * 11/1998 Ermel G06T 17/00

the broken line at the periphery of the graphical user

715/848

interface illustrates the display screen, and the remainder of

D437,859 S * 2/2001 Alvarez D14/489

the broken lines illustrate portions of the graphical user

D561,193 S * 2/2008 O'Mullan D14/487

interface. None of the broken lines form part of the claimed

D594,873 S * 6/2009 Onodera D14/488

design.

D604,308 S * 11/2009 Takano D14/486

The outermost set of broken lines and the broken line showing

D609,717 S * 2/2010 Yokouchi D14/486

of rounded shapes illustrate an electronic device,

D642,192 S * 7/2011 Arnold D14/487

the broken line at the periphery of the graphical user
